The ornamental design for a display panel with animated graphical user interface, as shown and described.

DESCRIPTION

FIG. 1 is a front view of the first image in a sequence for a display panel with animated graphical user interface, showing my new design; and,

FIG. 2 is a front view of the second image thereof. The broken lines of FIGS. 1 and 2 are for illustrative purposes only and form no part of the claimed design. The longer-incremented broken lines showing a portion of a display panel of a communications terminal illustrate environment and form no part of the claimed design. The images and text in shown in finer-incremented broken lines illustrate features of the transitional graphical user interface that form no part of the claimed design.

The appearance of the image transitions sequentially between the images shown in FIGS. 1 and 2, respectively. The process or period in which an image transitions to another image forms no part of the claimed design.
